UNITED STATES PATENT OFFICE.

WILLIAM JOSEPH RUSSELL, OF WOLVERHAMPTON, ENGLAND.

PUMP FOR LIQUIDS.

Application filed July 14, 1921. Serial No. 484,813.

To all whom it may concern:

Be it known that I, WILLIAM JOSEPH RUSSELL, a subject of the King of Great Britain, residing in Wolverhampton, England, have invented certain new and useful Improvements in Pumps for Liquids, of which the following is a specification.

My invention relates to improvements in that type of pump for liquids in which a reciprocating piston (this term including a plunger, bucket or the like) moves a column of liquid so that it acquires momentum sufficient to keep the column in movement after the termination of the power stroke and so that more liquid is drawn in by the moving column in the direction of flow and the valve or valves are closed only during the power portion of the stroke of the piston in question.

By the invention a pump of this kind is so constructed that the piston or part of it can move, during the power portion of the stroke, at a speed independent of that of certain parts of the driving mechanism.

In the known pumps the motion of the piston usually tends to be approximately harmonic, being derived from reciprocating driving mechanism comprising a rotating crank. The motion of the liquid on the other hand tends to be continuous.

Herein lies a defect, since the piston moves at a speed which varies during the power stroke while the speed of the liquid is substantially constant so that the impulse is applied by the piston only through a comparatively small portion of the stroke and shocks are liable to occur.

By this invention this defect is mitigated by making it possible for the piston to follow the movement of the liquid during the power portion of a stroke so that the impulse is applied more uniformly and may be prolonged through a considerably greater portion of the stroke than is the case when the piston must follow the speed of the driving mechanism.

The object may be obtained by the interposition between parts that reciprocate, of elastic devices. Thus in the commonest case there is a shaft tending to be rotated uniformly by an engine, a crank fixed to the shaft and the pump piston connected with the crank by the usual linkwork, forming a kinematic chain, the motion of the reciprocating parts being directly governed by the rotating shaft. By the invention the said

elastic devices are introduced into the kinematic chain somewhere between the rotating shaft and the piston or that portion of the piston which acts directly on the liquid. For instance, the piston may be in two or more parts with the elastic device between them, one or more of the parts may be itself the elastic device for instance, an air cushion on the end face of the piston; or the said device may be between the piston and the piston rod or connected parts, or between the shaft and the crank or in the crank itself.

During the period of impulse when the reciprocating parts tend to move faster than the liquid column, the elastic devices allow relative motion to occur and energy is stored by the elastic devices to be liberated again during the latter part of the impulse when the displaced parts regain their normal relative positions.

By using two or more pistons, each having elastic devices, the work may be uniformly shared between them although they operate to impart impulse simultaneously in the same direction. Suitable multiple pistons may be contrived to operate in succession so as to reduce the length of the periods between the impulses or to eliminate such periods, that is, to obtain in effect a continuous impulse of almost constant intensity—an exceedingly valuable result especially for high lift pumping. In the case of pumps having only one piston, only one valve or one set of valves is necessary, but for the purpose of priming, for starting up, a foot valve may sometimes prove useful.

The foregoing general statements will be further illustrated by reference to the accompanying diagrammatic drawings showing in Figures 1 to 15 sections and partial sections of several forms of pumps and accessories thereto in accordance with the invention.

Fig. 1 shows a part section of a simple form of pump. The bucket 1 having valves 2 works in a cylinder or barrel 3. Beneath the bucket is a spring 4 which at its lower end rests on or is held by a ring 5 attached to a cross-head 6. The latter is rigidly connected by rods 7 with the cross-head 8 and pump rod 9 which has vertical reciprocating motion. The rod 10 rigidly attached to cross-head 6 slides through a hole 13 in the bucket 1 and carries a collar 11 sliding

in a cylindrical extension 12 of bucket 1, thus keeping the latter normal to the axis of the barrel 3. Beneath the collar 11 is a spring or buffer 14.

5 The barrel 3 is expanded below its cylinder portion, as indicated, to form a bell shaped mouth facilitating introduction of the bucket.

10 Above the barrel is a taper pipe 15 and a pipe 16 of smaller diameter than the barrel and of sufficient length to provide the necessary mass of the liquid column.

15 The liquid column consists of the whole of the moving liquid in barrel 3 and pipes 15 and 16, but the liquid in pipe 16 is usually the main portion. The barrel in this case is of larger diameter than the pipe 16 to allow of suitable valve area in the bucket and to reduce the velocity of 20 liquid through the valves 2.

The operation is as follows:—

25 It is assumed that the pump is working normally, the rod 9, deriving its motion from a crank rotating uniformly. It is also assumed that the liquid column in barrel 3 and pipes 15 and 16 is moving with approximately uniform velocity in the direction of the arrow. Assume now that the cross-head 6 and attached parts are at their 30 lowest positions, and that bucket 1 is also at its lowest position in the barrel 3, all the parts just referred to being momentarily at rest with the crank on the dead centre. The bucket 1 will be in the position shown 35 with respect to the rod 10, collar 11, and springs 4 and 14; valves 2 will be open to allow the liquid drawn upwards by the momentum of the liquid column to pass through the bucket.

40 The cross-head 6 now begins its upward stroke with gradually increasing velocity, and the spring 4, preferably under initial compression, carries the bucket 1 upward with motion similar to that of cross-head 6.

45 The upward velocity of the liquid through and with respect to valves 2 gradually decreases until, at the moment when the velocity of the bucket attains that of the liquid in barrel 3, no liquid passes through

50 the valves which thereupon close in any known manner such as under the action of springs or elastic material.

The velocity of cross-head 6 now soon exceeds that of the liquid in barrel 3 and under 55 the action of spring 4 the bucket exerts pressure against the liquid above it, thus giving an impulse.

Although the velocity of the liquid column may a little later increase slightly 60 due to the impulse itself it will not alter in direct proportion to the velocity of the cross-head 6, nor is it desirable that it should do so; the spring 4 is, therefore, still further compressed, thus storing energy and 65 allowing the cross-head 6, rod 10 and other

attached parts to move upward relatively to bucket 1. The compression of spring 4 proceeds to a maximum and later in the upward stroke of 6 and attached parts as their velocity decreases below that of the liquid, 70 the spring 4 expands again giving out the energy stored by being compressed, and the bucket returns to the position relative to cross-head 6, rod 10, collar 11 and springs 75 4 and 14, which it had at the beginning of the impulse. At this moment the impulse is complete and the valves 2 again open to permit passage of liquid through them. At the moment when the bucket regains its 80 top position with regard to cross-head 6, it is moving with a certain velocity relatively to the collar 11, and the spring or buffer 14 prevents or minimizes the shock which might otherwise occur, due to the momentum of the bucket. 85

The springs must be of suitable proportions for the functions they have to perform, especially spring 4.

As this spring becomes further compressed 90 during an impulse the pressure exerted against the bucket, in turn to be exerted against the liquid column above it, will usually also be increased, but by the use of a suitable spring and initial compression this variation of pressure need not be 95 large, so that there is a more or less uniform pressure during the period of impulse. After the valves 2 re-open and during the return stroke the velocity of liquid 100 through the valves increases to a maximum approximately at the moment when the cross-head is travelling downwards at its maximum velocity. Thereafter as the velocity of cross-head and bucket decreases, the velocity of the liquid through the valves 105 decreases until at the dead centre of the crank the cycle of operations is completed.

In starting the pump from rest the pipes 110 16 and 17 and the barrel above the bucket may be primed by filling or partly filling with liquid. If the head $a-a$ of the liquid to be pumped is sufficiently high, it may lift the valves 2 and prime the pump sufficiently for starting.

The action in starting from rest is similar 115 to that just described except that at the slower velocities and with a shorter liquid column the various motions may be less regular and in particular the liquid column may even come to rest and partly return during the return stroke of the bucket. 120

By disconnecting rod 9 from above or disconnecting rod 7 from cross-head 8 and lowering the bucket clear of the lower end of barrel 3, the bucket and its valves are very 125 readily removed for inspection and repair. The leakage of liquid past the bucket and rod 10 is prevented or reduced to a minimum by the usual methods of packing.

The modification shown in Fig. 2 avoids 130

the perforation 13 of Fig. 1. In this case the rod 10 is attached to the bucket and the collar 11 works in the cylinder 12 attached to the cross-head 6. The spring or buffer 14^a performs the same functions as spring 14 in Fig. 1. Spring 4^a may assist or be used instead of spring 4 in Fig. 1.

There are many positions where springs giving the required effects may be introduced. Thus in Fig. 3 the upper end of cylinder 12 is partly closed to retain a spring 4^a between the closed end and collar 11.

Generally Fig. 3 is very similar to Fig. 1, but cross-head 6, rods 7, cross-head 8 and rod 9 are elastically connected by introducing springs 4^c, 14^c; 4^b, 14^b; 4^d, 14^d; and 4^e, 14^e respectively.

Springs 4^a, 4^b, 4^c, 4^d and 4^e act to assist spring 4 or one or more such springs may be used instead of spring 4. Springs 14^a, 14^b, 14^c, 14^d and 14^e have similar functions to spring 14.

Fig. 4 shows a somewhat modified and in some respects simpler arrangement. As before the bucket 1 provided with valves 2 works in barrel 3. In this case the cross-heads 6 and 8 are dispensed with, and the rod 10 is extended upwards above collar 11 as pump rod 7 to serve the same purpose as rods 7 and 9 in Fig. 1. Rod 7 slides in a gland 17 in the pipe 15. Springs 4^a and 14^a operate similarly to springs 4 and 14 respectively in Fig. 1, but other springs or suitable elastic devices may be used instead or in supplement.

Fig. 5 shows in section a type of bucket allowing a large valve area relatively to the diameter of the barrel 1. A series of similar 40 annular parts of increasing diameter 20^a, 20^b, 20^c and 20^d form the valve ports or apertures. These, together with annular parts 19, 21 and 22 (the last named being carried by spider 23 and from nave 24) are co-axially mounted on the cylindrical tube 12 and clamped together between collars 12^a and nut 12^b.

Rings 2^a, 2^b, 2^c and 2^d of suitable flexible and elastic material, lie on the upper flat surfaces of 20^a, 20^b, 20^c and 20^d and form the valves corresponding with valves 2 in Fig. 1. When liquid passes through the valves the rings 2^a, 2^b, 2^c and 2^d lift and turn upwards against the curved annular stops 18^a, 18^b, 18^c and 18^d.

After the passage of liquid the elasticity of the valves causes them to resume their normal flat shape and return to their seats.

The bucket leather or cup 24 is shown held in position between parts 21 and 22. The whole bucket may slide on rod 10 fixed to cross-head 6 not shown, which keeps it normal to the barrel.

Fig. 6 shows in section a pump with a valveless plunger, the valves 2 for liquid be-

ing in a stationary partition 25 held between the two pipes 26 and 15. In the centre of the valve partition 25 is a cylinder 3 wherein the piston or plunger 1 slides. The pump rod 7, driven by a crank or the like, slides in a gland 17 in pipe 16 and through the ends of piston 1, which are shaped to offer the minimum of resistance to the moving liquid. The rod 7 has a collar 11, between which and the ends of the piston are springs 4 and 14.

In normal operation the action is practically the same as that of Fig. 1.

The spring 4 is compressed and re-expands during an impulse whilst the valves 2 remain closed. Spring 14, similarly to spring 14 in Fig. 1, serves as a buffer to check the motion of the piston 1 when the latter attains its top position relatively to rod 7. It will be noted that the piston slides on rod 7 during the compression and expansion of spring 4.

The liquid may be raised from levels considerably below the valves 2, as at a—a, by providing a suction pipe 27, and as already mentioned a foot valve or valves 28 are sometimes useful for priming the pump with liquid for starting; during the normal operation of the pump these valves remain open, and allow the continuous passage of liquid. It is obvious that in a case where a bucket having valves is used, there may be additional valves in a stationary partition as in Fig. 6, and that there are many other ways than those shown by which the springs or elastic devices can be provided.

When cross-head such as 6 and 8 in Figs. 1 and 3 are used, they may themselves be formed of leaf springs to assist the other elastic devices, if any. Thus, in Fig. 7 the rod 9 corresponds with rod 9 of Fig. 1 and leaf spring 4^a, fixed to the end 8 of rod 9, acts as cross-head, and serves a similar purpose to that of spring 4 of Fig. 1. Buffer springs 14^a serve the purposes of springs 14 in Fig. 1 and the bar 11^a sliding on rods 7 performs the functions of collar 11. As in the case of spring 4 of Fig. 1, it is desirable that there shall be initial tension in spring 4^a.

It has already been mentioned that during the compression of springs 4, 4^a and elastic devices imparting the impulse, a useful purpose is served if the impulse is as constant as possible. Usually when an elastic device is compressed, or its configuration is altered, the pressure alters as the distortion increases. This may be minimized or entirely eliminated by systems of levers with or without cam and like devices. As an example of the latter, the fusee wheel of a spring clock or watch may be given.

In Fig. 8 is shown a convenient arrangement for fixing a pump, of the kind shown

in Fig. 1, to a well or pit. Two parallel beams or joists 29 are fixed to a wall of the pit and the barrel 3 is assumed to be provided with suitable external brackets which are bolted or otherwise fixed to the beams 29 near their lower end.

The upper ends of the beams carry bearings for a rotating shaft carrying a crank disc 30 with crank pin 31 connected with 10 slipper 32 sliding in slipper guide 33; this latter is also very conveniently fixed to the upper ends of beams 29.

The pipes 15 and 16 are fixed to and rest on barrel 3. The pump is driven by driving belt 34 and belt pulley 35.

In the illustrations so far described, the elastic devices have been one of the simplest, namely, metal springs, but any other suitable type of spring can be used, for instance, 20 pneumatic cushions which have advantages for large pumps.

In Fig. 9 such cushions are shown, rod 7 corresponding with rod 7 in Fig. 4.

Plate 36 attached to lower end of pump 25 rod 9 slides on the parallel rods 38, which secure at definite distance apart, plates 37 and 39, the former being connected with the upper end of rod 7.

Between plates 39 and 36 are four pneumatic tubes 4, inflated to the required degree, and a similar tube 14 is shown between plates 36 and 37.

During an impulse to the liquid column 35 the inflated cushions 4 act quite similarly to the springs 4 in Fig. 1, except as may be modified by the momentum of the solid parts between the cushions and the bucket, and the cushion 14 serves a similar purpose to that of spring 14.

During compression of the cushion, the 40 plates 39 and 36 slide on rods 9 and 38 respectively. Parts 40 represent guides to prevent displacement of the cushions.

The cushions 4 may be interconnected or 45 connected in common with a reservoir thus allowing the pressure of inflation to be more constant during compression.

By interposing suitably shaped distance 50 pieces between the cushions as at 41 in Fig. 9^a, a still more uniform tension on rod 7 may be obtained, for if the pressure in cushion 4 is approximately constant during compression of the cushions the effective area in contact with distance pieces 41 alters 55 very little, and thus the total lateral pressure will remain as constant as desired.

In Fig. 10 4^a represents inflated cushions 60 under initial pressure, either quite separate, or for convenience communicating with each other, and if desired to obtain more uniform pressure, all communicating with a common reservoir. They correspond with air cushions 4 of Fig. 9, and the inflated cushion 14^a, in this case annular, like 14 of Fig. 9, 65 serves the purpose of a buffer cushion. Rod

9 corresponds with rod 9 in Fig. 1 and rods 7 with rods 7 in Fig. 1.

Fig. 11 illustrates how the bucket 1 can be operated directly by air cushions. As in Fig. 1, the cross-head 6 is fixed to rods 7 and bucket 1 slides in barrel 3, the inflated cushions 4 being held between bucket 1 and cross-head 6 in similar manner to spring 4 in Fig. 1. Rod 10, collar 11, spring 14 and cushions 4 serve similar purposes to the parts 75 of like numbers in Fig. 1.

Other inflated cushions 42 between the bucket 1 and a flange 43 projecting from barrel 3, may suffice by acting as a spring to arrest, by compression, the upward motion 80 of the bucket at the end of its stroke, and by re-expansion to cause the downstroke, thus assisting or dispensing with the functions of parts 10, 14 and 11.

Also if the degree of inflation of 42 is sufficiently small during an impulse the liquid pressure may compress the cushions, so that the compression and subsequent expansion will supplement the effect of cushions 4.

It should be noted that if the bucket is 90 suitably guided, and if the surfaces of cushions 42 in contact with each other and with flange 43 and bucket 1 are liquid tight the barrel 3 may be dispensed with below flange 43 and all sliding and rubbing eliminated, this arrangement being, therefore, 95 very suitable for gritty liquid likely to score the barrel.

If there are two or more buckets or 100 pistons, each provided with elastic devices acting simultaneously to cause flow in the same direction, the buckets or pistons will share the work between them, the elastic devices being compressed and expanding together.

In Fig. 12, however, is shown a pump having 110 two buckets operated by cranks set at 180° to each other. Thus, when rod 7^a is at the top of its stroke, rod 7^b is at the bottom of its stroke. It will be seen that each bucket will operate practically independently of the other each giving an impulse every revolution of the cranks. Thus there are two impulses per revolution of the crank-shaft at equal intervals.

At slow speeds and during starting up, this type of pump has the advantage that it operates like any other pump having two sets of valves, and if desired may be independent of the momentum of the moving column for drawing in fresh liquid. It will 120 indeed function either way according to the speed of operation.

By introducing a third, fourth, or more buckets or their equivalent, it may be arranged that the impulse exerted by one bucket may not have ceased before that from another begins, so that a continuous pressure is obtained.

Fig. 13 illustrates a modification especial- 130

ly adapted for one, two, three, four or more buckets.

At the lower end of tube 1^a are valves 2^a, and the said tube is adapted to slide over the external surface of the lower end 3 of pipe 16 which corresponds with similar pipes 16 in other figures.

It is assumed that where necessary suitable packing is provided to prevent or minimize 10 leakage between pipe 3 and tube 1^a.

The side rods 7^a have similar functions to rods 7 in other figures and springs 4^a and 14^a act like similarly numbered springs in other figures.

15 Thus when rods 7^a move upwards with increasing velocity, it being assumed that the liquid column in 3 and 16 is moving upwards with considerable and fairly uniform velocity, the valves 2^a close substantially when the impulse begins, and springs 4^a then become still further compressed.

It is readily seen that all the functions of Figs. 1 and 2 are carried out in Fig. 13, and tube 1^a acts as the bucket in Fig. 1.

20 Another bucket in effect is readily provided by fitting another tube 1^b to slide outside tube 1^a and having similar valves 2^b, rods 7^b and springs 4^b and 14^b.

If the rods 7^a and 7^b are operated as in 30 Fig. 12 by cranks at 180°, similar effects regarding the frequency of impulses are obtained.

Again, three tubes telescoping over each 35 other may be used operated by three cranks at 120° and then there are three impulses per revolution, or four tubes operated by four cranks at 90° gives four impulses per revolution, and so on.

The bottoms of the tubes containing the 40 valves may be attached to the tubular sides elastically, say through the medium of inflated pneumatic cushions as shown in Fig. 11, and by this means additional elasticity is ensured.

45 In general, it is desirable to introduce the elastic devices, or part of them, as close to the liquid valves as possible.

In large pumps the seats of the valves themselves may be formed of inflated tubes.

50 The type of valve shown in Fig. 5 is naturally resilient and, therefore, very suitable for this pump.

A very simple system of employing multiple buckets or pistons is shown in Fig. 14. 55 A number of barrels, in this case 4, namely 3^a, 3^b, 3^c and 3^d are joined by bends. Each barrel has a bucket as at 1^a, 1^b, 1^c and 1^d; rods 7^a, 7^b, 7^c and 7^d, and the elastic devices are shown at 4^a, 14^a, 4^b, 14^b, 4^c, 14^c and 60 4^d, 14^d, but may of course be in any suitable position. Buckets 1^a and 1^b are operated by a common crank 31 and connecting rod 44, slipper 32 working in slipper guide 33, and the slipper 32 carries projecting arms 45^a and 45^b which impart the impulses through

elastic devices 4^a and 4^b in barrels 3^a and 3^b respectively. It will be noted that valves 2^a open upwards and valves 2^b downwards, and that 4^a gives an impulse upwards and 4^b downwards.

70

Thus although the two buckets are operated by a common crank the impulses are two per revolution as in the case of Fig. 12.

When another pair of barrels is used as at 3^c and 3^d, the crank 31^c operating them is preferably set at 90° to crank 31, so that the impulses occur between those governed by crank 31.

If 6 barrels are used with 3 cranks, the latter would be preferably set at 120° to one another, giving 6 impulses per revolution at equal intervals. The pipe 16 may be extended to any desired length for steadiness of working, but with suitable and sufficient elastic devices a much shorter length is required than in cases with fewer barrels. Suction pipe 27 leading to the liquid to be pumped may have a foot valve or valves as before to facilitate priming.

The type of pump shown in Fig. 6 may 90 also be amplified in this manner, as also may a modification of the type in Fig. 13.

In many cases it is advisable to vary the diameter of barrel and plain pipe to reduce as much as possible sudden changes in velocity or to economize material as has been shown in Figs. 1, 2, 3, 4, 6, 8 and 12.

95 Another arrangement is shown in Fig. 15, which, although not suitable for multiple pistons in series, has certain advantages due to simplicity of construction. The ram 1 works in barrel 3. Crank 31 rotates and through connecting rod 44 reciprocates part 5 which can slide in the ram 1, springs 4 and 14 are held preferably under some initial tension between part 5 and the ends of the ram 1. As part 5 moves to the right to impart impulse to the liquid column in 16, spring 4 is compressed similarly to springs 4 in previous figures and spring 14 prevents shock at the end of a period of impulse. Between the impulses valves 2 open to allow of the passage of fresh liquid to follow the moving column in 16.

100 During the impulse as the valves 2 are closed the liquid in pipe 27 must either come to rest, or if an elastic cushion is provided as at 46, compress this elastic cushion, but the motion of the liquid throughout the system is not continuous in the same sense 105 as in the previously described cases.

110 In certain cases instead of using inflated cushions as in Figs. 9 and 10, the required effect may be produced by using a piston working in a cylinder so as to compress an air cushion. To prevent leakage the piston may be covered with liquid, the rate of leakage being less for liquid such as thick oil than for a gas. In either case the leakage 125 can be made up by pumping in gas or liquid 130

in substitution for that which has leaked out.

I am aware that a spring has been inserted between the cross-head of a plunger pump for liquids and the plunger, but the pump does not operate in the manner herein defined, and the spring has not the function herein claimed.

Having thus described the nature of the 10 said invention and the best means I know of carrying the same into practical effect, I claim:

1. In a method of raising or forcing liquids which consists in moving by the 15 power portion of the stroke of a reciprocating piston a column of liquid so that it acquires momentum sufficient to keep the column in movement after the power portion of the stroke has ceased to act and so 20 that more liquid is drawn in by the moving column in the direction of the flow, the improvement which consists in prolonging the power portion of the stroke.

2. A pump including a piston, a means 25 for driving the piston, whereby a column of liquid is given sufficient momentum to cause the column to continue to move after the power stroke of the pump has ceased to act and so to draw in more liquid in the direction 30 of flow, and means positioned between the driving means and the piston adapted to permit the piston substantially to follow the movement of the liquid during the power portion of a stroke independently of the motion 35 of the parts of the driving means.

3. A pump including a piston, a means for driving the piston, whereby a column of liquid is given sufficient momentum to cause the column to continue to move after the 40 power stroke of the pump has ceased to act and so to draw in more liquid in the direction of flow, and a resilient device interposed between the driving means and the piston adapted to permit the piston substantially to follow the movement of the liquid during the power portion of a stroke independently of the motion of the parts of the driving means.

4. A pump including a piston, a means 50 for driving the piston, whereby a column of liquid is given sufficient momentum to cause the column to continue to move after the power stroke of the pump has ceased to act and so to draw in more liquid in the direction 55 of flow, a resilient device interposed

between the driving means and the part of the piston adapted to permit the piston substantially to follow the movement of the liquid during the power portion of a stroke independently of the motion of the parts 60 of the driving means, and an elastic buffer adapted to prevent shock at the end of the power portion of a stroke.

5. A pump including a piston, means including a rotating crank for driving the 65 piston, whereby a column of liquid is given sufficient momentum to cause the column to continue to move after the power stroke of the pump has ceased to act and so to draw in more liquid in the direction of flow, and 70 means interposed between the driving means and the piston for permitting the piston to follow the movement of the liquid during the power portion of a stroke independently 75 of the motion of the parts of the driving means.

6. A pump including a piston, means including a rotating crank for driving the piston, whereby a column of liquid is given sufficient momentum to cause the column to 80 continue to move after the power stroke of the pump has ceased to act and so to draw in more liquid in the direction of flow, and a resilient device interposed between the driving means and the piston adapted to 85 permit the piston to follow the movement of the liquid during the power portion of a stroke independently of the motion of the parts of the driving means.

7. A pump including a piston, means comprising a rotating crank for driving the piston, whereby a column of liquid is given sufficient momentum to cause the column to continue to move after the power stroke of the pump has ceased to act and so to draw in more liquid in the direction of flow, a resilient device interposed between the driving means and the part of the piston in contact with the liquid, said device being adapted to permit said part of the piston 95 to follow the movement of the liquid during the power portion of a stroke independently of the motion of the parts of the driving means, and an elastic buffer adapted to prevent shock at the end of the power portion 100 of a stroke.

In testimony whereof I have signed my name to this specification.

WILLIAM JOSEPH RUSDELL.
